UNITED STATES PATENT OFFICE

168,861

BELL

Sajjan Singh Sarna, New York, N. Y.

Application June 18, 1952, Serial No. 20,242

Term of patent 7 years

(Cl. D29—1)

To all whom it may concern:

Be it known that I, Sajjan Singh Sarna, a citizen of the United States of America, residing at New York, State of New York, have invented a new, original, and ornamental Design for a Bell, of which the following is a specification, reference being had to the accompanying drawing, forming a part hereof.

Fig. 1 is a front elevational view of a bell, showing my new design;

Fig. 2 is a side elevational view thereof;

Fig. 3 is a top plan view thereof; and

Fig. 4 is a side elevational view of the side opposite to that shown in Fig. 2.

I claim:

The ornamental design for a bell, as shown.
SAJJAN SINGH SARNA.
